LOAD BEARING GLAZED BUILDING BLOCK

Albert Henderson, Edgewood, Pa., assignor to
William P. Witherow, Pittsburgh, Pa.

Application February 13, 1937, Serial No. 125,575

4 Claims. (Cl. 72—41)

This invention relates to a building block to be used in the laying up of walls capable of transmitting light.

Light-transmitting walls have usually been composed either of glass tile or brick, although it has also been proposed to place glass panes over the ends of the usual voids extending through building blocks, and then lay the blocks on their sides to provide for the transmission of light through the wall. The cost of a wall composed of glass tile or brick is excessive, especially if the wall has to bear any load, and the amount of light transmitted through a wall composed of blocks having glass panes set in the ends of the usual voids is relatively slight. It is an object of my invention, therefore, to provide a relatively inexpensive wall construction capable of transmitting a substantial amount of light therethrough.

In accordance with my invention, I employ a building block of any suitable material, such as concrete, having one or more voids extending therethrough from top to bottom. I provide window openings in one or more of the side walls of the block and place flanged glass plates in said openings. The blocks are laid up in a wall with their voids vertical, whereby the glazed side walls are effective to transmit light through the wall. The glass plates are firmly embedded in the block by the shrinkage of the concrete therearound and actually bear a substantial part of the load on the block.

I preferably manufacture the block of my invention by disposing flanged glass plates in a mold with the plates themselves engaging a wall of the mold and the flanges thereof engaging a core extending through the mold. I then pour a cementitious mix around the core and glass plates to form the complete block.

Further features of my invention will become apparent as the following detailed description thereof proceeds. The accompanying drawings illustrate a preferred embodiment and practice with certain modifications. In the drawings,

Fig. 1 is a perspective view of one form of block according to my invention;

Fig. 2 is a perspective view of a flanged glass plate adapted to be incorporated in a block;

Fig. 3 is a sectional view through the block of Fig. 1, taken along a medial horizontal plane;

Fig. 4 is a sectional view taken through a mold along a medial horizontal plane, illustrating the method of manufacture;

Fig. 5 is a view similar to Fig. 3, showing a modified construction;

Fig. 6 is a fragment of Fig. 5 to enlarged scale;

Fig. 7 is a perspective view of a modified form of block;

Fig. 8 is a vertical sectional view taken through one of the windows in the block of Fig. 7;

Fig. 9 is a perspective view of a further modification;

Fig. 10 is a sectional view thereof similar to Fig. 8;

Fig. 11 is a sectional view taken through one form of wall construction in accordance with the invention; and

Fig. 12 is a similar view showing a further form of wall.

Referring now in detail to the drawings, a block 10 composed of concrete or other suitable material has voids 11 extending vertically therethrough, leaving side walls 12, end walls 13 and a center wall 14. The voids 11 extend through the block from top to bottom thereof and are preferably formed by cores during the molding of the block. Window openings 15 are provided in a plurality of the side or end walls 12 and 13. Fig. 1 shows such window openings in both the side walls 12 only. Flanged glass plates 16 overlie the openings 15 and make a tight joint with the edges of the openings. The flanges 17 of the plates 16 taper inwardly and their outer surfaces are serrated, as at 18, for a purpose which will appear presently. The bevel on the outside of the glass flanges permits their easy removal and replacement in case of breakage.

Fig. 4 illustrates diagrammatically the method which I prefer for manufacturing blocks of the type shown in Fig. 1. A mold 20 of any suitable construction is provided with cores 21 preferably movable relative to the side walls of the mold through suitable openings in a pallet 22. With the cores 21 in position, I dispose a plurality of plates 16, as shown in Fig. 4, with their flat surfaces engaging the mold walls and their flanges engaging the cores 21. Filler blocks 23 of any suitable material are disposed between the glass plates and the cores to prevent seepage of the plastic material. Reinforcing members 24 are positioned adjacent the bottom and top and ends of the mold before and after the placing of the glass plates 16. Concrete or other suitable plastic material is then poured into the mold around the cores and the glass plates. After partial setting, the pallet is raised to eject the block from the mold, by apparatus such as that shown and de-

scribed in my copending application Ser. No. 62,965, filed Feb. 8, 1936, for Method and apparatus for making concrete articles. After further setting, the filler blocks 23 are removed and the 5 blocks are then cured. The serrations 18 on the flanges 17 of the plates 16 cause the latter to form a firm bond with the concrete. Also, the shrinkage of the cement grips the glass, thereby permitting the glass to help carry the load.

10 Fig. 5 shows a modification in which the end walls 13 and the middle web 14 of the block shown in Fig. 1 are provided with window openings having plates 16 disposed therein. As shown in Fig. 6, the flanges 17 of the plates 16 are beveled 15 adjacent their edges, as at 25. These edges are thus adapted for contact with each other, as shown in Figs. 5 and 6, as well as with the cores 21.

10 Figs. 7 and 8 illustrate a further modified form 20 of block composed of concrete or the like and having window openings therein. Each window opening is provided with a pair of plates 16 disposed edge to edge, as shown in Fig. 8.

15 Figs. 9 and 10 show a block having single 25 plates 16 seated in its windows.

Fig. 11 illustrates a wall composed of blocks 10. As there shown, the rays of light may pass through the wall at an angle because the voids 11 of the several courses of blocks are vertically 30 aligned. Transverse glass plates 26 may be disposed between courses to prevent any chance of dust or dirt settling on the glass.

Fig. 12 shows the use of blocks, such as that shown in Figs. 9 and 10, to serve as intermediate 35 courses or as a coping course in a wall composed of blocks, such as that shown at 10.

The invention is characterized by numerous advantages over constructions previously known. The cost of a wall composed of the block shown is 40 much less than that of a wall composed of glass tile or brick. As indicated in Figs. 11 and 12, furthermore, the invention permits light to be transmitted through the wall at various angles. A much greater amount of light will thus be 45 transmitted through a wall composed of a wall of my invention than through one composed of cored blocks having the ends of their voids only

glazed. The block of my invention, furthermore, has considerable structural strength. The glass plates themselves have a high compression strength and are firmly bonded to the concrete forming the block. The great strength of the 5 glass in compression (100,000 lbs. per sq. in.) makes it safe to design the block with relatively thin walls of plastic material and large window openings, increasing the amount of light transmitted. The method of manufacture disclosed 10 is simple and relatively inexpensive.

Although I have illustrated and described but a preferred form of the invention and certain modifications thereof, it will be understood that changes in the construction and practice described may be made within the scope of the following claims.

I claim:

1. A wall composed of successive courses of blocks, each having spaced side walls and vertical 20 voids therebetween, window openings in said side walls and window lights in said openings whereby a ray of light may pass through a window of one block, partially through the voids of said one block and a block in an adjacent course, and 25 then through a window of said last mentioned block.

2. A wall as defined by claim 1, characterized by transverse light-transmitting members disposed between adjacent blocks. 30

3. A building block having a void extending vertically therethrough, window openings in two opposite side walls of the block, and flanged glass plates seated in said openings, the material of which the block is composed being firmly bonded 35 to the flanges of said plates whereby to transmit at least part of the load on the block to said plates.

4. A building block having a void extending vertically therethrough, window openings in two 40 opposite side walls of the block, and glass plates seated in said openings, the material of which the block is composed being firmly bonded to the edges of said plates whereby to transmit at least part of the load on the block to said plates. 45

ALBERT HENDERSON:
